UNITED STATES PATENT OFFICE.

NORVAL ASKELAND, OF ORLAND, CALIFORNIA.

TIE-WIRE FOR CEMENT-SACKS.

1,266,902.

Specification of Letters Patent. Patented May 21, 1918.

Application filed March 21, 1918. Serial No. 223,737.

To all whom it may concern:

Be it known that I, NORVAL ASKELAND, a citizen of the United States, residing at Orland, in the county of Glenn, State of California, have invented a new and useful Tie-Wire for Cement-Sacks; and I do hereby declare the following to be a full, clear, and exact description of the invention, such as will enable others skilled in the art to which 10 it appertains to make and use the same.

The present invention relates to a tie wire for securing cement sacks and the like, and has for its object to provide a device of this character which embodies novel features of 15 construction whereby it will hold the mouth of the sack securely closed while the sack is being handled, but which can be quickly removed by the fingers when it is desired to empty the contents of the sack.

20 Further objects of the invention are to provide a device of this character which can be inexpensively formed from a single length of wire, which can be easily applied to the sack, and which can be quickly removed without any annoyance or delay, and 25 without the necessity of using a knife or special tool.

With these and other objects in view, the invention consists in certain novel combinations and arrangements of the parts as will 30 more fully appear as the description proceeds, the novel features thereof being pointed out in the appended claims.

For a full understanding of the invention, 35 reference is to be had to the following description and accompanying drawings, in which:—

Figure 1 is a perspective view of a sack having one of the tie wires applied thereto. 40 Fig. 2 is an enlarged perspective view of the tie wire, showing the ends thereof as brought together into operative position.

Fig. 3 is a similar view showing the ends of the tie wire as released from engagement 45 with each other.

Corresponding and like parts are referred to in the following description and indicated in all the views of the drawings by the same reference characters.

50 The tie is formed from a single strand of wire 1 which is of a sufficient length to secure the mouth of a cement sack A or the like, and to provide a finger engaging loop. One extremity of the wire is returned and 55 twisted to provide a loop 2, while an intermediate portion of the wire is doubled upon

itself at 3, an eye 4 being formed at the bent portion of the wire, and this eye being insertible through the loop 2 when the device is in operative position. The free end of the 60 wire is bent to provide a finger engaging loop E and then inserted through the eye 4, thereby preventing the eye from being pulled through the loop 2 and holding the tie members securely in operative position. 65 However, when it is desired to remove the tie, it is merely necessary to insert a finger through the loop E and forcibly withdraw the free end of the wire strand from the eye 4, whereupon the latter will pull through 70 the loop 2 and release the mouth of the sack A.

From the foregoing it will be understood that the wire is bent to provide a main loop F which encircles the mouth of the sack to 75 hold it securely closed, and a finger receiving loop E which is arranged at one side of the main loop. When the device is applied to a sack, as indicated by Fig. 1, the main loop F encircles the mouth of the sack 80 and holds it securely closed, although in order to remove the tie member it is merely necessary to insert a finger through the loop E and forcibly pull the free end of the wire through the eye 4. This can be quickly ac- 85 complished without any annoyance or delay, and without the use of a knife or other special tool. The free end of the wire is shown as provided with a pair of crimps 5, one of which is normally positioned on each 90 side of the eye 4, thereby preventing the wire from being accidentally pulled or pushed through the eye 4 in either direction while handling the sack. These crimps will not, however, interfere with the removal of 95 the tie in any manner when it is desired to empty the contents of the sack.

Having thus described the invention, what I claim as new and desire to secure by Letters Patent, is:—

1. A tie for sacks, including a wire strand having a loop at one extremity thereof, an intermediate portion of the wire being doubled upon itself to provide an eye which is insertible through the loop, while the other 105 extremity of the wire is insertible through the eye to prevent it from pulling through the loop, the wire strand thereby providing a main loop for securing the bag, and a finger receiving loop for releasing the bag. 110

2. A tie for sacks, including a wire strand having a loop at one extremity thereof, an

intermediate portion of the wire being doubled upon itself to provide an eye which is insertible through the loop, the other extremity of the wire being bent to provide a finger receiving loop and inserted through the eye to prevent the eye from pulling through the first mentioned loop, the said free end of the wire being crimped to prevent it from being accidentally pulled out 10 of position.

3. A tie for sacks, including a wire strand having a loop at one extremity thereof, an intermediate portion of the wire being doubled upon itself to provide an eye which is insertible through the loop, the other extremity of the wire being bent to provide a 15

finger receiving loop and inserted through the eye to prevent the eye from pulling through the first mentioned loop, the said free end of the wire being provided with a pair of crimps which are normally positioned on each side of the eye to prevent accidental disengagement of the end of the wire from the eye. 20

In testimony whereof I have signed my name to this specification in the presence of 25 two subscribing witnesses.

NORVAL ASKELAND.
